UNITED STATES PATENT OFFICE.

JAMES MONTGOMERY, OF NEW YORK, N. Y.

IMPROVED APPARATUS FOR CORRUGATING METAL.

Specification forming part of Letters Patent No. 102,349, dated May 10, 1870.

To all whom it may concern:

Be it known that I, JAMES MONTGOMERY, of the city, county, and State of New York, have invented a new and Improved Apparatus for Corrugating Sheet Metal, of which the following is a specification.

My machinery is so constructed and arranged that the iron to be corrugated is laid upon a carriage having at the edge next the operator a raised flange or stop, against which the rear edge of the sheet to be corrugated is placed and held by the gripping-bar. The carriage is pushed forward to enter the front edge of the sheet between the longitudinally-fluted rolls; but in order to insure the gripping of the sheet at its extreme edge, so that the edges of different sheets will come to the same part of the corrugation, and thus adapt them to fit together, I employ a stop adjustable for different widths of iron and serving to limit the forward movement of the carriage. To change the machine for a new width of iron, the stop is carefully adjusted for the first sheet by means of a suitable setting-screw, after which it will operate with great rapidity and perfect accuracy on successive sheets of uniform width. In some cases I propose to employ, instead of a stop which may limit the advance of the table to a point where the corrugated rolls can grasp the extreme edge of the plate, as above set forth, a temporary stop, which will prevent the table advancing quite so far, and, being retracted automatically at a certain period in the revolution of the rolls, will insure accurate uniformity in the introduction or feed of the sheets.

In the accompanying drawings, Figure 1 represents the apparatus in elevation. Fig. 2 represents a transverse section thereof.

Like letters of reference indicate corresponding parts.

A B is a pair of rolls, made hollow in order to combine lightness with strength, and for the purpose of passing through them water or air to keep them cool when the metal is rolled hot, as in the case of boiler-plate. These rolls may be driven by a band-wheel, C, in customary manner, and are formed on their peripheries with corresponding and intermeshing longitudinal ribs and grooves, for the purpose of corrugating sheet metal which is passed between them.

D D are the customary adjusting-screws to regulate the proximity of the rolls.

E is a shelf or table for the reception of bundles of iron sheets in convenient position for them to be taken one by one.

F is a carriage for feeding the sheets to the rolls. At the rear edge of the said carriage is a flange, G, against which the rear edges of the sheets rest and where they are held by a clamp, H.

I is a stop to limit the forward movement of the table, and itself adjustable by a screw-rod, J, operated by a crank, K.

L is a chute to receive and conduct the corrugated sheets from the rolls.

Instead of the stop I, I may employ an automatic stopping and releasing device, consisting of a sliding catch, M, projecting downward in front of the carriage and retracted at proper periods by cams on the upper roll, A, acting on a lever, N, to the free end of which the catch M is pivoted.

O O O represent various parts of the frame.

Operation: A bundle of metal sheets of uniform width being unbound and laid upon the table E, the operator draws the upper sheet onto the carriage F with its rear edge resting against the flange G. He then grasps this edge firmly with the clamp H. The action presses the edge more firmly against the flange. The carriage F is then moved slowly forward, the stop I being by means of the screw-rod J and crank K moved gradually forward in front of the carriage to allow the advance of the latter. This slow movement is continued until the extreme forward edge of the sheet is caught by the rolls A B, which draw the sheet from the carriage, and at the same instant the operator ceases to move the stop I, which thus forms a gage to limit the forward movement of the carriage to a point where it will permit the front edge of the sheet to be seized by the rolls. The stop having been thus adjusted, the operator can then feed successive sheets of uniform width with great rapidity, and the corrugations of the various sheets will precisely correspond, because the first grip of the rolls is at the extreme edge of each sheet.

If preferred, a sliding catch, M, may be employed to stop the carriage F at a point just short of where it would permit the gripping of

the sheet. In this case the said catch, being withdrawn automatically by the lever N, actuated by a suitable cam at a certain period in the rotation of the rolls will cause the successive sheets to be fed to the rolls while the latter are in precisely corresponding positions, so that their effect on the different sheets will be uniform, locating the corrugations of all of them in the same position relatively to the edge of each sheet.

For some purposes rolls will be prepared specially for each width of iron, the circumference of the rolls and the number and size of the corrugations thereon being so arranged that an accurate number of corrugations will be produced on each sheet, and the two edges of each sheet being at corresponding parts of the corrugations the sheet will be reversible. The chute L receives the corrugated sheets from the rolls and conducts them to a suitable truck or car running upon rails, so that when each car receives a load of sheets it may be

quickly removed and replaced by an empty one.

I claim as my invention—

1. The improved machine herein described for corrugating sheet metal, the same consisting of a pair of fluted hollow rolls, A B, carriage F G, for feeding sheets to the said rolls, and adjustable screw-stop I, to control the carriage, substantially as set forth.

2. The clamp or gripper H, in combination with the carriage F G, substantially as and for the purpose set forth.

3. The combination of the stop I, screw J, carriage F G, and clamp H.

4. The arrangement of the table E, carriage F, and rolls A B, substantially as shown and described.

JAMES MONTGOMERY.
